UNITED STATES PATENT OFFICE

2,484,740

DERMATOME HOLDER

John D. Reese, Philadelphia, Pa.

Application November 2, 1945, Serial No. 626,279

4 Claims. (Cl. 128—305)

1

This invention relates to surgical instruments, more particularly to dermatomes, and has for an object to provide an improved device for supporting a dermatome while the latter is being prepared for use.

Another object of the invention is to provide a dermatome support wherein the supporting structure is disposed entirely at one side of the dermatome, during use, whereby access to the other side of the dermatome is unobstructed.

When a graft-transfer strip is being applied to a drum-type dermatome, in the manner disclosed in applicant's copending application Serial No. 618,523, filed September 25, 1945, and now Patent Number 2,442,434, it is desirable that the semi-cylindrical drum be so supported that the graft-transfer strip may be applied thereto without the necessity of inserting the strip between opposed supporting members at opposite sides of the dermatome. Also, it is necessary that both of the operator's hands be free for use in securing the graft-transfer strip to the dermatome and that the dermatome shall be securely supported in the desired position. Therefore, a further object of the invention is to provide a dermatome support which will effect these results.

These and other objects are effected by the invention as will be apparent from the following description and claims taken in accordance with the accompanying drawings, forming a part of this application, in which:

Fig. 1 is a perspective view of a support embodying the principles of the present invention;

Fig. 2 is a front elevational view of the structure shown in Fig. 1, with a broken line showing of a dermatome supported thereon in position for attachment of a graft-transfer strip thereto;

Fig. 3 is an elevational view of the right side of the structure as shown in Fig. 2;

Fig. 4 is a view similar to that shown in Fig. 3, except that the dermatome, shown in broken lines, is disposed in position for coating of the convex surface thereof with a cement;

Fig. 5 is an enlarged fragmentary sectional view, taken along the line V—V of Fig. 1, looking in the direction indicated by the arrows;

Fig. 6 is an enlarged fragmentary sectional view, taken along the line VI—VI of Fig. 1, looking in the direction indicated by the arrows;

Fig. 7 is an enlarged fragmentary sectional view, taken along the line VII—VII of Fig. 1, looking in the direction indicated by the arrows; and

Fig. 8 is an enlarged fragmentary sectional view, taken along the line VIII—VIII of Fig. 1, looking in the direction indicated by the arrows.

Referring now to the drawings more in detail, the reference character 10 indicates, in its entirety, a dermatome support comprising a rectangular base 11, of sufficient mass to prevent up-

setting of the apparatus during use, and a standard 12 extending upwardly therefrom and secured thereto by a pair of flat-headed screws 13. Preferably, the standard 12 is in the form of a flat metallic strip, and to brace it in the direction of its lesser cross-sectional dimension, a strut 14 has its upper end secured to the upper part of the standard 12 by a pair of screws 15, and is inclined downwardly and away from the standard 12 to its lower end which is secured to the base 11 by screws 16.

Preferably, the standard 12 and its bracing strut 14 are secured to the base 11 near one corner of the latter. Integral with the standard 12 is an arm 17 which projects forwardly therefrom and carries at its outer end a spindle 18, preferably of circular cross section, which projects laterally and horizontally from one side of the arm towards the more distant side of the base (Fig. 2), and substantially midway between the front and rear edges of the base (Fig. 4). The free end of this spindle 18 is preferably rounded, or streamlined, as at 19, in order that the semi-cylindrical body member 101 of a dermatome 100 may be easily slipped onto the spindle (Figs. 2, 3 and 4).

The spindle is circular in cross section, and of a diameter to slide freely in a pair of aligned openings provided in the opposed side walls 102 and 103 of the dermatome body member 101 near their semi-cylindrical edges and substantially midway of the lengths thereof. The spindle is provided, near its inner end, with a flange 21 adapted to abut the side of the arm 17 when the stud terminal portion 22 is peened or riveted in the arm's opening 23 (Fig. 7). The flange 21 serves as a spacer to limit inward movement of the dermatome on the spindle, toward the standard 12.

In normal use of a dermatome of the type which the apparatus of the present invention is intended to support, and which is fully described, both as to structure and use, in applicant's copending application, previously identified, it may be desirable to support the dermatome in either of two positions, the first of these positions being illustrated in Figs. 2 and 3, by the broken lines, and the second being illustrated in Fig. 4, likewise by broken lines.

In the first position (Figs. 2 and 3), the body member 101 of the dermatome 100 is disposed with its concave-convex wall 104 downward, so that the operator may have ready and unobstructed access to the mechanism, disposed within the body member 101 adjacent the ends of the semi-cylindrical wall 104, by which the terminal portions of the graft-transfer strip are secured to the body member with the intermediate portion of said graft-transfer strip taut against the

3

outer convex surface 105 of the concave-convex wall 104.

The dermatome body member 101 is prevented from rotating out of this position by a pin 25 (Fig. 5) projecting from the inner side of the standard 12, in parallel relation to the spindle 18. As the dermatome nears its innermost position on the spindle 18 when being assembled, the pin 25 enters a mating opening 106 provided in the side wall 103 of the dermatome, thereby holding 10 the body member 101 against rotation on the spindle 18. Preferably, the pin 25 has a flange 26 abutting the inner side of the standard 12 and functioning in the manner of the flange 21 on the spindle 18, to limit inward movement of 15 the dermatome on the pin 25.

To prevent accidental outward movement of the dermatome on the spindle 18, in a direction away from the standard 12, with consequent disengagement of the pin 25 from its mating opening 106 in the dermatome side wall, a latch 28 is pivotally mounted in the opening 29 of the standard 12 by a pin 30 (Fig. 8). This latch 28 has a head portion 31 provided with a downwardly-opening notch 32 adapted to latch over the adjacent upper edge 107 of the dermatome side wall 103 (Figs. 2 and 3). A spring 33 presses against the top of the latch at one side of the pivot pin 30 to normally urge the latch head 31 down into latching position. Preferably, the 30 outer lower corner of the latch head is tapered or beveled, as at 34, so that the latch will be lifted by contact of the edge of the dermatome side wall therewith as the dermatome is slid onto the spindle 18. The latch is provided with a handle portion 35, by which the latch may be easily disengaged from the dermatome when it is desired to remove the latter from the support.

It is desirable that while a graft-transfer strip is being applied to the dermatome body member 101, the knife 108 and its supporting structure, including the posts 109, be disposed above the body member where they will not interfere with the operation of securing the graft-transfer strip about the convex surface of the body member. To this end, an arm rest 37 is fixedly secured to the upper end of the standard 12 in position to engage one of the dermatome posts 109 and thereby support the entire quadrangle formed by the posts 109, the shaft 110 on which they are mounted, and the blade 111 and its carrying structure 112 (Figs. 2 and 3).

It will be apparent from consideration of Figs. 2 and 3 that with the blade 111 and its supporting structure supported on the rest 37, in the manner illustrated, a graft-transfer strip can be secured to one end of the dermatome body member and then freely drawn around the convex surface 105 without any interference, particularly as the spindle 18 is supported at one end only, thereby leaving the opposite side of the dermatome free and readily accessible.

In the second of the two positions in which the dermatome may be supported by the structure of the present invention (Fig. 4), the body member convex surface is positioned upwardly and the posts and blade hang down therefrom. In this position, the convex surface 105 is readily accessible for the coating thereof with a suitable cement or adhesive, as is common practice in the use of instruments of the type illustrated.

To prevent swinging of the body member on the spindle 18, a pin 46 is mounted on the inner face 75 of the standard 12 for reception in a mating

4

opening 115 existing in the dermatome structure (Figs. 3 and 4).

While the invention has been shown in one form, it will be obvious to those skilled in the art that it is not so limited but is susceptible of various changes and modifications without departing from the spirit thereof.

What is claimed is:

1. In a dermatome supporting structure, a base adapted to rest on a horizontal surface, a standard carried by said base, a horizontal spindle carried by said standard and adapted to support a dermatome thereon for pivotal movement thereabout, and means carried by said standard for retaining in a predetermined position a dermatome supported on said spindle.

2. In a dermatome support, a base adapted to rest on a horizontal surface; a standard carried by said base; a horizontal spindle supported at one end only from said standard, said spindle being adapted to support a dermatome slid thereonto from the other end thereof; a pin projecting horizontally from the standard and receivable in a mating opening in said dermatome for holding said dermatome against rotation on the spindle, and a latch adapted to prevent accidental withdrawal of the dermatome from the spindle when the dermatome is held against rotation by said pin.

3. In a dermatome holder, a rectangular base, a standard extending upwardly from said base near one corner thereof, an arm extending horizontally from said standard in a plane parallel to one edge of said base, and a dermatome-supporting spindle extending horizontally from said arm at right angles to said one edge of the base and approximately equidistant from the two edges of the base which are adjacent said one edge of the base, and means for retaining a dermatome in supported position on the horizontal spindle.

4. A holder for a dermatome of the type comprising a body member having a convex surface, a pair of parallel posts at opposite sides of the body member, blade-supporting mechanism carried by the posts at one end thereof and bridging the space therebetween, and means supporting the posts at their other ends from the body member for movement of the blade-supporting mechanism parallel to, and at a predetermined distance from, the body member convex surface; said holding comprising a base, a standard extending upwardly from said base, a horizontal spindle carried by said standard and adapted to extend through aligned openings in the side walls of the dermatome body member when supporting the latter, and a rest carried by said standard against which the structure comprised by the blade-mounting mechanism and the posts may rest in a position above the dermatome body member and away from the body member convex surface.
